ATTENUATOR

Arthur H. Maciszewski, Julius J. Hupert, Richard Goldstein, and Tadeusz Szubski, all of River Forest, Ill., assignors to A.R.F. Products, Inc., River Forest, Ill., a corporation of Illinois

Original application May 13, 1954, Ser. No. 429,547, now Patent No. 2,881,315, dated Apr. 7, 1959. Divided and this application Apr. 21, 1958, Ser. No. 729,825

5 Claims. (Cl. 333—81)

This invention relates to an attenuator and particularly to an attenuator of the wave guide type.

It is an important object of the present invention to provide an improved radio frequency output attenuator of the wave guide type.

Yet another object of the invention is to provide an improved radio frequency output attenuator which is responsive only to the voltage induced by the inductive coupling mode and in which the coupling can be adjusted.

In connection with the foregoing object it is a still further object to provide an attenuator in which there is practically no mistuning of the principal radio frequency tank circuit due to the degree of coupling thereto by the attenuator.

Figure 1 is a view in vertical section through a radio frequency output attenuator made in accordance with and embodying the principles of the present invention;

Figure 2 is a view partially in cross section of the attenuator of Figure 1 substantially as seen in the direction of the arrows along the line 2—2 of Figure 1;

Figure 3 is a view in vertical cross section of the attenuator of Figures 1 and 2 substantially as seen in the direction of the arrows along the line 3—3 of Figure 2;

Figure 4 is an end view of the attenuator of Figure 1 as viewed from the left hand end in Figure 1;

Figure 5 is an enlarged partial view in cross section substantially as seen in the direction of the arrows along the line 5—5 of Figure 4 and illustrating the construction of the capacitive mode suppressor; and

Figure 6 is a schematic electrical diagram of the attenuator of Figures 1 to 5 and showing the relation thereof to associated circuit components.

Referring now particularly to Figures 1 and 6 of the drawing, there is shown an output radio frequency attenuator made in accordance with the embodying the principles of the present invention, the attenuator being generally designated by the numeral 191. The attenuator includes in general a pick-up coil 192, one end of which is grounded as at 194 and the other end 196 of which is connected to the electronic equipment to be tested. Coil 192 is inductively coupled to an associated coil such as a coil 134 in a tank circuit. An electrostatic shield 198 is provided to prevent excitation of the pick-up loop or coil 192 by capacity coupling. The pick-up coil 192 is positioned within a metal tube 200 so that the tube and coil operate on the inductive-coupling mode as a wave guide below cutoff.

A pick-up loop or monitor wire 202 is provided, the monitor wire extending into the tube 200 and being positioned between the pick-up loop 192 and the electrostatic shield 198. The position of the monitor loop 202 is adjustable. A connection is made from the monitor loop 202 through a rectifier 204, a resistance 206 a first inductance 208 and a second inductance 210 to a speaker. A capacitor 212 by-passes the resistance 206 to ground.

The wave guide tube 200 is preferably circular in cross section and is open at both ends, one end being provided

2

with an outturned attachment flange 214 which is used to attach the attenuator to the chassis of the signal generator. The other end of tube 200 has a plurality of slots formed therein which receive three flat pieces or straps of metal 216 which form the electrostatic shield 198. From Fig. 4 it will be seen that the straps 216 are disposed parallel with each other with the center strap lying along a diameter of tube 200. It will be further seen that the orientation of the straps 216 is in a plane perpendicular to the longitudinal axis of the monitor wire 202. The shape in plan view of the straps 216 is best seen in Fig. 5, the straps being substantially rectangular in shape but having a semi-circular cut-out 218 along one of the longer edges thereof, the cut-out being along the edge positioned inwardly of tube 200 and being positioned about the longitudinal center line of tube 200.

The upper side of tube 200 as viewed in Fig. 1 has an elongated slot 220 formed therein through which monitor wire 202 extends. Monitor wire 202 is fixedly attached to the end of a second tube 222 whose external diameter is slightly less than the internal diameter of tube 200 whereby tube 222 slides easily within tube 200. An abutment member 224 positioned on tube 222 extends upwardly through slot 220 and serves to center tube 222 with respect to slot 220 and thus in turn centers the monitor wire 202. The other end of tube 202 carries a collar 226 fixedly attached thereto which includes the adjusting mechanism that will be described later.

Positioned within tube 222 and slidable therein is a substantially cylindrical plunger 228. The left hand end of plunger 228 as viewed in Fig. 1 has a longitudinal aperture therein which receives a resistor 230. One end of resistor 230 is attached to plunger 228 in a part-circular depression therein as at 232 and the other end of resistor 230 is connected to the pick-up loop 192. A longitudinal hole through plunger 228 receives a co-axial cable 234 which has the center lead 196 therein attached to one end of the pick-up loop 192. The other end of the co-axial cable 234 is provided with the usual coupling 236.

In the actual installation the end of the tube 200 carrying the electrostatic shield straps 216 is positioned adjacent to the coil in the tank of a variable frequency oscillator. It is desirable to adjust the radio frequency injection into the attenuator by moving the monitor wire 202 and the pick-up loop 192 toward and away from the shield and straps 216 and the associated feed coil. Also the value of the attenuation must be adjustable by moving the pick-up loop 192 toward and away from the monitor loop 202. To this end mechanism is provided for moving tube 222 inwardly and outwardly with respect to tube 200 which is ordinarily fixed and separate means is provided for moving plunger 228 inwardly and outwardly with respect to tube 222.

Referring to Figs. 2 and 3 the mechanism for procuring the desired movement of tube 222 and plunger 228 will be described in detail. The portion of tube 222 which normally extends outwardly and to the right with respect to flange 214 as viewed in Fig. 2 has attached thereto by means of screws 238 a geared rack 240. A gear 242 mounted on a shaft 244 is provided to engage with rack 240.

Shaft 244 is permanently positioned with respect to flange 214 and a rotary movement of shaft 244 and the attached gear 242 causes movement of tube 222 inwardly and outwardly with respect to tube 200. This accordingly adjusts the position of monitor wire 202 with respect to the associated tank coil, this adjusting motion being accomplished without affecting the attenuation between monitor wire 202 and pick-up loop 192.

The mechanism for moving plunger 228 with respect

to tube 222 is mounted on the upper portion of member 226 as viewed in Figs. 2 and 3. A slot 246 is formed in plunger 228 at the right hand thereof as viewed in Fig. 2 and within the slot is mounted a geared rack 248 held in position by two screws 250. The highest point on the teeth of rack 248 is disposed well within the circumference of tube 228. A slot is formed at the right hand end of tube 222 and into this slot extends a toothed gear 252 which cooperates and meshes with the teeth on rack 248. Gear 252 is mounted on a rotating shaft 254 which is journaled in a pair of bearing blocks 256. In order to insure that there is no lost motion in the gear and rack arrangement, a frame 258 is provided that supports a pair of springs 260 that are under compression. The springs 260 press against the bearing blocks 256 and thus in turn press gear 252 against rack 248 to eliminate lost motion and inadvertent misadjustment therebetween.

The attenuator of Fig. 1 through 5 insures that only the desired excitation is obtained on pick-up loop 192, the desired excitation being that corresponding to the inductive coupling mode. This is obtained by providing the electrostatic shield 198 including the straps 216 between the associated feed coil of the RF tank and the pick-up loop 192. Since the electrostatic shield 198 is immobile and since the monitor loop moves behind the shield, there is practically no mistuning of the main RF tank including the associated feed coil due to the variations of the position of the monitor loop 202. Furthermore, the amount of RF injection into the attenuator can be adjusted by turning shaft 244 without affecting the value of the attenuation and the value of the attenuation can be adjusted by turning shaft 254 thereby changing the distances between pick-up loop 192 and the monitor wire 202 without changing the RF injection into the attenuator.

This application is a division of the copending application Serial No. 429,547 filed May 13, 1954 for Device for Generating Signals.

It will be seen that there has been provided an attenuator of the wave guide type which fulfills all of the advantages and objects set forth above. Although a specific example of the attenuator has been given for purposes of illustration, it is to be understood that various changes can be made therein without departing from the spirit and scope of the invention. Accordingly, the invention is to be limited only as set forth in the following claims.

We claim:

1. A radio frequency attenuator for operation with an associated source of radio frequency radiation on the inductive-coupling mode as a wave guide below cutoff, comprising a first tube adapted to have one of the open ends thereof disposed toward and fixedly positioned with respect to the radiation source, said first tube having a longitudinal slot therein, a second tube positioned within said first tube and being slidably adjustable therein, a monitor member mounted on and carried by said second tube within said first tube and extending outwardly through said slot a distance that is small compared to the transverse dimension of said first tube whereby said monitor member is inductively coupled to the radiation source, means positioned in said one end of said first tube forming an electrostatic shield suppressing the capacitive-coupling mode between said monitor member and the radiation source, a pickup member positioned within said second tube and being slidably adjustable therein to receive radiation from said monitor member, first adjustment means to move said second tube including said monitor member and said pickup member simultaneously with respect to said first tube to adjust the amount of radiation injected into said attenuator without changing the attenuation between said monitor member and said pickup member, and second adjustment means to move said pickup member with respect to said monitor member without moving said monitor member

with respect to said first tube whereby to adjust the attenuation between said monitor member and said pickup member without changing the amount of radiation injected into said attenuator.

- 5 2. A radio frequency attenuator for operation with an associated source of radio frequency radiation on the inductive-coupling mode as a wave guide below cutoff, comprising a first tube adapted to have one of the open ends thereof disposed toward and fixedly positioned with respect to the radiation source, said first tube having a longitudinal slot therein, a second tube positioned within said first tube and being slidably adjustable therein, a monitor member mounted on and carried by said second tube within said first tube and extending outwardly through said slot a distance that is small compared to the transverse dimension of said first tube whereby said monitor member is inductively coupled to the radiation source, an abutment member fixedly mounted on said second tube and extending into said slot and engaging the edges thereof to hold said monitor member spaced from the edges of said slot, a plurality of metal straps mounted across said one end of said first tube to provide an electrostatic shield suppressing the capacitive-coupling mode between said monitor member and the radiation source, a plunger positioned within said second tube and being slidably adjustable therein, a pickup member mounted on said plunger within said second tube to receive radiation from said monitor member, first adjustment means to move said second tube and said plunger simultaneously with respect to said first tube thereby to move simultaneously said monitor member and said pickup member with respect to the associated radiation source to adjust the amount of radiation injected into said attenuator without changing the attenuation between said monitor member and said pickup member, and second adjustment means to move said plunger with respect to said second tube thereby to move said pickup member toward and away from said monitor member without moving said monitor member with respect to said first tube whereby to adjust the attenuation between said monitor member and said pickup member without changing the amount of radiation injected into said attenuator.
- 10 3. The radio frequency attenuator as set forth in claim 2, wherein the monitor member is a wire, and the straps are positioned along chordal lines of the first tube and are disposed perpendicular to the axis of said monitor wire.
- 15 4. A radio frequency attenuator for operation with an associated source of radio frequency radiation on the inductive-coupling mode as a wave guide below cutoff, comprising a first tube adapted to have one of the open ends thereof disposed toward and fixedly positioned with respect to the radiation source, said first tube having a longitudinal slot therein, a second tube positioned within said first tube and being slidably adjustable therein, a monitor member mounted on and carried by said second tube within said first tube and extending outwardly through said slot a distance that is small compared to the transverse dimension of said first tube whereby said monitor member is inductively coupled to the radiation source, means positioned in said one end of said first tube forming an electrostatic shield suppressing the capacitive-coupling mode between said monitor member and the radiation source, a plunger positioned within said second tube and being slidably adjustable therein, a pickup member mounted on and carried by said plunger within said second tube and positioned to receive radiation from said monitor member, first adjustment means including a first rack and pinion acting between said first and second tubes to move said second tube including said monitor member and said plunger including said pickup member simultaneously with respect to said first tube to adjust the amount of radiation injected into said attenuator without changing the attenuation between said monitor member and said pickup member, and second
- 20 5. The radio frequency attenuator as set forth in claim 4, wherein the monitor member is a wire, and the straps are positioned along chordal lines of the first tube and are disposed perpendicular to the axis of said monitor wire.
- 25 6. The radio frequency attenuator as set forth in claim 4, wherein the monitor member is a wire, and the straps are positioned along chordal lines of the first tube and are disposed perpendicular to the axis of said monitor wire.
- 30 7. The radio frequency attenuator as set forth in claim 4, wherein the monitor member is a wire, and the straps are positioned along chordal lines of the first tube and are disposed perpendicular to the axis of said monitor wire.
- 35 8. The radio frequency attenuator as set forth in claim 4, wherein the monitor member is a wire, and the straps are positioned along chordal lines of the first tube and are disposed perpendicular to the axis of said monitor wire.
- 40 9. The radio frequency attenuator as set forth in claim 4, wherein the monitor member is a wire, and the straps are positioned along chordal lines of the first tube and are disposed perpendicular to the axis of said monitor wire.
- 45 10. The radio frequency attenuator as set forth in claim 4, wherein the monitor member is a wire, and the straps are positioned along chordal lines of the first tube and are disposed perpendicular to the axis of said monitor wire.
- 50 11. The radio frequency attenuator as set forth in claim 4, wherein the monitor member is a wire, and the straps are positioned along chordal lines of the first tube and are disposed perpendicular to the axis of said monitor wire.
- 55 12. The radio frequency attenuator as set forth in claim 4, wherein the monitor member is a wire, and the straps are positioned along chordal lines of the first tube and are disposed perpendicular to the axis of said monitor wire.
- 60 13. The radio frequency attenuator as set forth in claim 4, wherein the monitor member is a wire, and the straps are positioned along chordal lines of the first tube and are disposed perpendicular to the axis of said monitor wire.
- 65 14. The radio frequency attenuator as set forth in claim 4, wherein the monitor member is a wire, and the straps are positioned along chordal lines of the first tube and are disposed perpendicular to the axis of said monitor wire.
- 70 15. The radio frequency attenuator as set forth in claim 4, wherein the monitor member is a wire, and the straps are positioned along chordal lines of the first tube and are disposed perpendicular to the axis of said monitor wire.
- 75 16. The radio frequency attenuator as set forth in claim 4, wherein the monitor member is a wire, and the straps are positioned along chordal lines of the first tube and are disposed perpendicular to the axis of said monitor wire.

adjustment means including a second rack and pinion acting between said second tube and said plunger to move said pickup member with respect to said monitor member without moving said monitor member with respect to said first tube whereby to adjust the attenuation between said monitor member and said pickup member without changing the amount of radiation injected into said attenuator.

5. The radio frequency attenuator set forth in claim 4, wherein the pickup member is a loop of wire having 10

one end thereof connected through a resistor to said plunger and having the other end thereof connected to the center conductor in a radio frequency co-axial cable carried by the plunger.
